CLAIM

The ornamental design for a front door panel for vehicle as shown and described.

DESCRIPTION

The patent or application file contains at least one drawing executed in color. Copies of this patent or patent application publication with color drawing(s) will be provided by the Office upon request and payment of the necessary fee.

1. Front door panel for vehicle
- 1.1 is a front elevation view of a front door panel for vehicle, embodying my new design;
- 1.2 is a rear elevation view thereof;
- 1.3 is a left side elevation view thereof;
- 1.4 is a right side elevation view thereof;
- 1.5 is a top plan view thereof;
- 1.6 is a bottom plan view thereof;
- 1.7 is a left front perspective view thereof; and
- 1.8 is a left rear perspective view thereof.

1 Claim, 8 Drawing Sheets
(8 of 8 Drawing Sheet(s) Filed in Color)
